UNITED STATES PATENT OFFICE.

JAMES H. SCHOONMAKER, OF WINONA, MINNESOTA, ASSIGNOR OF TWO-THIRDS TO HENDERSON D. MORSE AND NATHANIEL C. GAULT, BOTH OF SAME PLACE.

LIGHTNING-ROD.

SPECIFICATION forming part of Letters Patent No. 364,605, dated June 7, 1887.

Application filed September 28, 1886. Serial No. 214,736. (No model.)

To all whom it may concern:

Be it known that I, JAMES H. SCHOONMAKER, a citizen of the United States, and a resident of Winona, in the county of Winona and State of Minnesota, have invented certain new and useful Improvements in Lightning-Rods; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of this invention, and is a side view. Fig. 2 is a detail, partly a side view and partly in section. Fig. 3 is also a detail, and shows one of the outside strands. Fig. 4 is a cross section of the lightning-rod, much enlarged.

My invention relates to lightning-rods; and it consists in the construction and novel combination of parts, as hereinafter described and claimed.

Referring by letter to the accompanying drawings, A designates a section of lightning-rod constructed in accordance with my improvements.

B designates the central hollow core of the rod, which I make from a strip of zinc by drawing it through a die. The core B is covered with sheet-copper C by means of a die. Zinc and copper are preferable for this purpose, but any other good conducting ductile metal may be used.

D is an outside strand of the rod or rope, which is made as follows: A hollow wire, E, is made by drawing a strip of copper or other ductile metal through a die. Around this hollow wire E are wound or twisted a sufficient number of small wires, F, to perfectly and evenly cover it. Small zinc wires F are preferable for this purpose, but any soft wire may be used. The small rope thus formed is then covered with copper or other ductile metal, thereby forming the strand D. A sufficient number of these strands D to evenly

cover the central hollow core, B, are then firmly and evenly wound around the hollow core B by means of machinery constructed for that purpose, which machinery gives each of the strands D a reverse twist while they are being wound around the central core, B. The reverse twist mentioned causes the completed conductor to retain the twist perfectly, and to thereby retain its form.

I am aware that a lightning-rod composed of solid iron wires covered with copper and wound or twisted together has been invented which, however, if made of sufficient size to be a good lightning-conductor, is so heavy and unwieldy as to render it impracticable to use as a lightning conductor, and I make no claim thereto. A lightning-rod consisting of hollow copper wires wound or twisted together has also been invented. This rod will not retain the twist, and is not strong enough for a lightning-conductor, as it is easily broken, and I make no claim to that form herein. Furthermore, a lightning-rod composed of hollow zinc wires covered with copper and wound or twisted together was patented on June 28, 1881, by myself, and is open to some of the objections above named, and I make no claim thereto in this application.

Having described this invention, what I claim, and desire to secure by Letters Patent, is—

1. The combination, with the hollow core, of the strands formed of hollow wires, around which a number of small soft wires are twisted and incased in a covering of copper, substantially as specified.

2. The combination, with a hollow core lined and covered with copper, of the strands formed of hollow wires, around which are twisted a number of small soft wires and incased in a covering of copper, said strands being twisted around the core, substantially as specified.

In testimony whereof I affix my signature in presence of two witnesses.

JAMES H. SCHOONMAKER.
